COMBINED CONTAINER AND COVER FOR REFUSE, GOODS AND THE LIKE

Melvin S. Shutt, Bartlesville, Okla., and Thomas E. Salisbury, Lake Forest, Ill., assignors to Phillips Petroleum Company, a corporation of Delaware

Filed July 17, 1967, Ser. No. 7,817

Term of patent 14 years

(Cl. D49—33)

FIG. 1

The rear and side, not shown, have substantially the same appearance as the front and side, respectively, shown.

We claim:

The ornamental design for a combined container and cover for refuse, goods, and the like, as shown and described.
